UNITED STATES PATENT OFFICE.

JOSEPH PRESTON CRIBB, OF SOUTHSEA, ENGLAND.

OVERHEAD ELECTRIC TROLLEY-WIRE.

SPECIFICATION forming part of Letters Patent No. 716,988, dated December 30, 1902.

Application filed September 8, 1902. Serial No. 122,552. (No model.)

To all whom it may concern:

Be it known that I, JOSEPH PRESTON CRIBB, a subject of the King of the United Kingdom of Great Britain and Ireland, residing at 76 5 Montgomerie road, Southsea, in the county of Hampshire, England, have invented new and useful Improvements in Connections with Overhead Electric Trolley-Wires, of which the following is a specification.

10 This invention relates to improvements in connection with overhead electric trolley-wires, the object being to provide means for interrupting the passage of the current when a trolley-wire breaks, and so prevent injury to 15 persons round about.

In carrying my invention into effect I proceed as follows, making reference to the accompanying drawings, wherein—

Figure 1 is a side view showing how the 20 current passes; Fig. 2, a sectional side view showing how the current is interrupted when the trolley-wire breaks, and Fig. 3 an end view.

I provide two parallel cheeks *a*, separated 25 by a cross-piece *b*, the whole being made of one piece of metal or joined up. Upward through the cross-piece *b* is passed a bolt *c*, having a square shoulder to prevent it turning around, and between the cheeks *a* is bolted 30 a block of ebonite or other insulating material *d*, having through it a hole to firmly hold the copper rod or bridge *e* of sufficient length to extend considerably beyond each 35 end of the block *d*, the ends of the said bridge *e* being made conical. The shape of the cheeks *a* is such as to provide two ears *f*, between which are pivoted on bolts *g* the "trips" *h*, having insulating-bushes *i*, bored 40 so as to allow the trips to turn freely on the bolts *g*. The trips *h* have upstanding portions *j*, each provided with a conical hole to receive one end of the bridge *e*. Each of the trips *h* is bored at *k* to receive the opposing ends of trolley-wire *l*, the lengths of the parts so bored

being such as will prevent the opposing ends 45 of the wire coming in contact with one another. The trolley-wires *l* are soldered or otherwise fastened in the holes *k*, and while each part of the wire remains unbroken the upstanding ends *j* are in contact with the ends 50 of the bridge *e* and the current passes from one part of the wire up its respective trip across the bridge down the other trip to the other part of the wire. When, however, the wire breaks, the respective trip overbalances 55 and causes the upstanding end *j* to fall away from the end of the bridge *e*, and so interrupt the passage of the current.

What I claim as my invention, and desire to secure by Letters Patent, is—

In an appliance for interrupting the passage of the current on the breaking of an overhead electric trolley-wire; two cheeks facing one another; a cross-piece connecting the cheeks at one end; a bolt passed upward 65 through the said cross-piece; an insulating-block between the said cheeks; a conical-ended copper rod passed lengthwise through the said insulating-block and having its ends extending considerably therebeyond; an ear at each 70 of the free corners of the cheeks; a cross-bolt passed through each opposing pair of ears; a "trip" to each of the said bolts and having an insulated hole to turn freely on the said bolts and between the cheeks of the appliance; 75 vertical extensions of each "trip" to form removable contacts with their respective conical ends of the longitudinal copper rod above mentioned and horizontal extensions of each trip to carry the ends of the trolley-wire, substantially as hereinbefore described.

In testimony whereof I have signed my name to this specification in the presence of two subscribing witnesses.

JOSEPH PRESTON CRIBB.
